(57) **CLAIM**

The ornamental design for a foldable storage box, as shown and described.

DESCRIPTION

FIG. 1 is a perspective view of the foldable storage box in an unfolded or flattened configuration of the present application;

FIG. 2 is a perspective view of the foldable storage box of FIG. 1 in a partially unfolded configuration;

FIG. 3 is a perspective view of the foldable storage box of FIG. 1 in an unfolded but flattened configuration;

FIG. 4 is a perspective view of the foldable storage box of FIG. 1 in a partially folded configuration;

FIG. 5 is a perspective view of the foldable storage box of FIG. 1 in a folded but open configuration;

FIG. 6 is a perspective view of the foldable storage box of FIG. 1 in a folded and closed configuration;

FIG. 7 is a front elevation view of the foldable storage box of FIG. 6;

FIG. 8 is a top plan view of the foldable storage box of FIG. 6;

FIG. 9 is a bottom plan view of the foldable storage box of FIG. 6;

FIG. 10 is a back elevation view of the foldable storage box of FIG. 6;

FIG. 11 is a right side elevation view of the foldable storage box of FIG. 6; and,

(Continued)

FIG. 12 is a left side elevation view of the foldable storage box of FIG. 6.
